UNITED STATES PATENT OFFICE.

CARL F. INGOLD, OF MILWAUKEE, WISCONSIN, ASSIGNOR TO MILWAUKEE OPTICAL MANUFACTURING COMPANY, OF MILWAUKEE, WISCONSIN, A CORPORATION OF WISCONSIN.

EYEGLASS-FRAME.

1,203,624.

Specification of Letters Patent. Patented Nov. 3, 1916.

Application filed April 17, 1916. Serial No. 91,515.

To all whom it may concern:

Be it known that I, CARL F. INGOLD, a citizen of the United States, residing at Milwaukee, county of Milwaukee, and State of Wisconsin, have invented new and useful Improvements in Eyeglass-Frames, of which the following is a specification.

My invention relates to improvements in eye-glass frames.

10 The object of my invention is to provide means whereby a set of lens-clamping bands may have their ends secured together independently of the bridge connection and independently of the nose clamps, whereby the 15 nose clamps may be removed and replaced without disengaging or releasing the lenses and whereby either lens may be released and removed without affecting the nose clamps or their actuating springs.

20 In the drawings—Figure 1 is a front elevation, one of the sets of clamping lugs being illustrated in vertical section. Fig. 2 is a sectional view on line 2—2 of Fig. 1. Fig. 3 is a fragmentary view, showing the clamping lugs in vertical section and slightly separated. This view also embodies a slight modification of the interlocking means.

Like parts are identified by the same reference characters throughout the several 30 views.

Each of the lenses A is encircled by a clamping band or strap B, one end of which is permanently secured to the abutment lug C of the nose bridge C', while the other end 35 of the band is secured to a lug D adapted to fit against the end surface of the abutment C, the two members C and D constituting clamping lugs. These lugs are preferably formed to interlock, a projection C'' on the 40 abutment lug C being adapted to engage in a corresponding recess in the margin of the lug D. Both of these lugs are centrally apertured to receive a connecting post E, which is preferably rigidly secured to the 45 abutment lug C. At its lower end, the post E is provided with a screw-threaded socket adapted to receive a clamping screw F, the head F' of which bears against the under surface of the lug D.

50 The upper end of the post E is provided with a similar screw G engaged in a threaded socket in the upper end portion of the post, and having a head G' against which the actuating spring H of the nose guard I is 55 adapted to bear. The nose guard or clamp

I is provided with a turning plate J, interposed between the lower end of the spring H and the lug or abutment C, the spring H being connected at h with the turning plate J. The post E passes loosely through an 60 aperture in the plate J. K is an operating thumb piece of ordinary construction whereby the nose clamp or guard may be actuated against the tension of the spring H to releasing position. The upper extremity of 65 the spring H is extended from beneath the screw head G' in the form of an arm L which engages the clamping band B near its connection with abutment lug C, whereby the spring is prevented from unwinding. 70

The lug D loosely engages over a lower end of the post E and is held up against abutment lug C solely by the head F' of the clamping screw F. Therefore, when screw F is removed, the lug D may be swung 75 downwardly, thereby releasing lens A. The post E being rigidly secured to the abutment lug C, it is obvious that the nose guard I will not be affected and that spring H will 80 not be disturbed. This is an important feature of my invention since the parts are extremely small and when the spring H is released, careful work is required to replace it under proper tension. It is also difficult, 85 when replacing spring H, to hold it in position while the screw G is being replaced in capping relation to post E. Therefore, with my improved construction, frequent replacement of the lenses can be accomplished easily and quickly by merely removing screw F which holds the lug D in position. I also attach considerable importance to the interlocking member C'', since 90 this prevents any oscillatory movement of the lug D upon the lug C. While I have 95 described the screw F as a clamping screw, it is not essential to my invention that this screw should forcibly press the member D against member C. It will be sufficient if the screw F holds the lug D in approximate 100 contact with the lug C, since the interlocking projection C'' may be utilized to prevent movement.

In Fig. 3 I have illustrated the band B and clamping lugs C and D in releasing position. This view is also slightly modified from the construction shown in Fig. 1, in that the interlocking projection C'' is formed on the lug D and is adapted to project into a recess in the lug C. 105 110

I claim—

1. The combination with a lens strap, of a set of clamping lugs, each secured to one end of said strap, a spring actuated nose guard mounted upon one of the lugs and means for clamping the lugs together independently of the nose guard mounting.
2. The combination with a lens engaging strap provided at its respective ends with clamping lugs, a nose bridge permanently connected with one of said lugs, a spring actuated nose guard mounted upon one side of the lugs, a projection on the opposite side of said lug, the other lug being socketed to receive said projection, and a clamping screw adapted to enter said projection and arranged to bind said lugs together.
3. The combination with a lens engaging strap provided at its respective ends with clamping lugs, a nose bridge permanently connected with one of said lugs, a spring actuated nose guard mounted upon one side of the lugs, a projection on the opposite side of said lug, the other lug being socketed to receive said projection and a clamping screw adapted to enter said projection and arranged to bind said lugs together, said lugs being formed to interlock with each other at one side of said projection.
4. An eye-glass frame including the combination with a nose engaging strap, of a pair of clamping lugs, each connected with

one end of the strap, a post on one lug socketed in the other, a clamping screw connected with said post and adapted to bind the lugs together and an interlocking member on one of the lugs, socketed in the opposing lug adjacent to said post and adapted to prevent pivotal oscillation of the lugs upon said post.

5. The combination with a lens engaging band or strap, of a pair of lenses each secured to one end of the strap, a post extending through one of the lugs and removably socketed in the other lug, a clamping screw adapted to engage one end of said post to bind said lugs together, a nose guard mounted on the other end of said post, a removable post cap, and a spring interposed between the said cap and a portion of the nose guard, said spring having one end connected with the nose guard and the other end projected into engagement with the lens strap, said parts being organized to permit independent separation of the clamping lugs or of the nose guard and spring substantially as described.

In testimony whereof I affix my signature in the presence of two witnesses.

CARL F. INGOLD.
